11 Claims. (CL 18—56)

1

This invention relates to methods of covering or wrapping objects with sheet materials. In this specification and in the appended claims, the words "cover," "covering," "wrapping" and the like are used in a broad sense to refer not only to packaging operations wherein a sheet material is wrapped completely around an object, but also to other arts and operations wherein a sheet material forms a part of or is associated with only part of a complete article.

In wrapping or packaging articles of commerce prior to this invention, it has been customary to employ substantially non-stretchable materials such as paper, fabric, foil, and cellulose film known commercially as "cellophane." Such materials are cut or otherwise provided in blank size and shape of area greater than the surface area of the particular article to be wrapped or covered. Sufficient excess material must always be used to enable the edge portions thereof to be relatively lapped.

As is well known, when non-stretchable wrapping material is used to cover a curved surface, it becomes wrinkled as the necessary crowding of the wrapping material takes place. One example of such wrinkling may be seen in the commercial use of holland cloth or the cellulose film known commercially as "cellophane" to cover the cemented or tacky side of a blow-out patch used as an automobile tire accessory. Another example of the wrapper and also of the excess of wrapping material over the area to be wrapped when non-stretchable material is used to wrap an article with a curved surface is seen in the common use of paper to wrap oranges. With the prior art material, round or irregular-shaped articles could not be wrapped without wrinkling, and all such objects in addition to those having flat sides and geometrical symmetry required an amount of wrapping material considerably in excess of the total surface area of such article or articles. In other words the prior art practices have been objectionable for several reasons and it is the object of the present invention to overcome such objections.

An important feature of the invention in its broad aspect is to provide a novel method for wrapping or covering in whole or in part various articles with a minimum of material and with freedom from wrinkles and the like.

More specifically, the invention contemplates the use of a film or sheet of heat-stretchable and heat-sealable material, one type of which is disclosed, for example, in the Calvert Patent No. 1,989,632, such material (a rubber hydrohalide

2

or a rubber hydrochloride film) being manufactured by the Goodyear Tire & Rubber Company of Akron, Ohio, and sold commercially under the name "Pliofilm." This material is characterized by its extreme flexibility and slight stretchability under normal conditions and by its resistance to moisture penetration. I have discovered that I can stretch this material very extensively when it is heated to within certain temperature ranges without injuring or otherwise detracting from either its appearance or its other properties. I take advantage of this discovery in practicing my invention by causing the film or sheet, while heated, to conform to the shape and size of article being wrapped, and preferably I stretch or expand the film or sheet very considerably in some instances whereby to effect substantial savings in material as well as to enhance the appearance of the wrapping and to make possible the neat wrapping of any object regardless of its shape. The sheet may be heated over its entire area or over any desired portion of its area dependent upon the requirements of a particular wrapping operation.

25 By way of example, but without limitation, it is here pointed out that the invention may be employed in the wrapping or covering of fruits, vegetables, confections, and other articles. In conjunction with any of the above mentioned or other articles, it is proposed to stretch the film or sheet to conform it to the shape of the object independently of the object, as by differential fluid pressure. Thus, in applying a cover to an umbrella, a blank of the heat-stretchable material may be applied to the face of a suitable cavitied mold and there held by its edges. Then by the application of heat in any desired manner, the material may be softened and caused to assume the shape of the mold cavity, preferably by differential fluid pressure. Subsequently, the shaped blank may be assembled with an umbrella frame and its edges turned over and secured in any preferred way. This assembling operation may be done either in the shaping mold or entirely apart therefrom. It is to be noticed, however, that in this form of the invention, the umbrella frame or equivalent article is not completely enfolded by the sheet material, but is merely covered in part and in this respect it differs from the other embodiment herein disclosed.

Another practice of the invention contemplates a complete enclosure of the object by converting two substantially flat blanks by stretching into complementary cover sections approxi-

inating the shape of the object and then placing the two cover sections over the object and sealing them together as one. Thus, the two blanks may be anchored in an air-tight manner around the perimeters of two complementary unheated mold cavities approximating the shape of the object and then, after they have been heated to impart to them the requisite stretchable and sealable properties, stretched into the mold cavities by vacuum and shaped accordingly. The object may then be placed in the mold cavities and the latter, with the vacuum still maintained, brought together into mating relation to seal the two stretch-shaped blanks together around the object as a complete unitary cover.

In the accompanying drawings:

Fig. 1 is an elevation of an umbrella embodying the invention;

Fig. 2 shows a sheet of rubber hydrochloride or other suitable material placed in hoops after the fashion of the ordinary practice in embroidery work;

Fig. 3 is a forming mold shown in operative position while heat is being applied to the rubber hydrochloride and before the vacuum line is open the dotted line therein indicating the position of the rubber hydrochloride after the vacuum line has been opened;

Fig. 4 is a convex storage form for the umbrella covers;

Fig. 5 is a concave working form used in applying the cover to the umbrella ribs;

Fig. 6 is a fragmentary sectional view similar to Fig. 2 and showing a modified form for holding the film;

Fig. 7 is a fragmentary view of the mold for receiving the parts of Fig. 6;

Fig. 8 is a view showing the formed sheet as it is removed from the mold of Fig. 7;

Fig. 9 is a transverse sectional view through still another form of apparatus for practicing the invention;

Fig. 10 is a similar view illustrating a different step in the method; and

Fig. 11 is an enlarged fragmentary sectional view on line 11—11 of Fig. 10.

Reference will first be made to Figs. 1 to 8, which illustrate the manner in which a cover for an umbrella, parasol or the like may be made and applied.

As shown in Fig. 1, the invention contemplates a cover of rubber hydrochloride 209 secured upon an umbrella frame of any ordinary or preferred construction, the one illustrated comprising radial ribs 210 connected by adjustable links 211 to a central seam 212, and it may be provided with any desired form of handle 213 and with a protecting tip of any preferred construction.

In practicing this form of my invention a sheet of appropriate material such as rubber hydrochloride 209 approximately .0015" thick and of proper area, (after being heat treated and stretched) for the umbrella to be covered is fastened between an outer hoop 215 and an inner hoop 216 in the usual manner employed in putting goods in embroidery hoops. The outer hoop 215 is preferably of aluminum and the inner hoop 216 may be of wood, rubber or any material that facilitates the assembly of the hoops. The outer hoop 215 extends some distance above the inner hoop for reasons disclosed hereinafter.

After the sheet 209 has been placed in said hoops, the hoops are placed on the ledge 217 of the mold 218. The inside diameter of the hoop

216 is such that a substantially air-tight fit between the surfaces 219 of the mold and 220 of the hoop is effected. The top of the hoop 215 becomes in effect the upper rim of the mold 218, and it will be seen that the top of hoop 215 extends above the top of the hoop 216.

The concave shape of the inside of mold 218 is designed with a curvature substantially of that of the umbrella surface to be covered and the mold 218 is provided with a platen 221 which is hingedly connected in any usual manner to the mold as at 222, the platen being provided with a counter-balance weight 223 to facilitate raising the platen to open position so that the molded umbrella cover may be removed from the mold and another to be molded may be placed. The platen 221 is provided with a steam chamber 224 being supplied with steam through inlet and outlet pipes not shown but installed by any standard method recognized by steam fitters. The function of the platen is to heat the sheet of rubber hydrochloride and it is to be understood that the heat may be applied from electrical units, hot air or otherwise. However, it has been found that in this particular form of the invention the best results are obtained by heating the rubber hydrochloride by radiated heat from a platen as shown, the surface of the platen being spaced apart from the rubber hydrochloride 209 approximately $\frac{1}{16}$ " when the mold is closed. It will be observed, as shown in Fig. 3, that the hoop 215 is designed to hold the plate 221 the desired distance from the blank or sheet 209. Rubber hydrochloride is extensible to a restricted degree in normal atmospheric temperatures but not sufficiently extensible at such temperature to mold to the degree necessary for my purpose. It has been found, however, that as the temperature of the rubber hydrochloride is raised it becomes more extensible until, at approximately 250° F., it will be extensible enough for my purpose. I permit the platen 221 to remain in position shown in Fig. 3 until the temperature of the rubber hydrochloride is raised to approximately 250° F. and then open a valve (not shown) in any ordinary vacuum line 224 which extends from the chamber 225, the chamber being formed by the inside surface of the mold and the sheet 209. The partial vacuum formed in this chamber causes the sheet 209 to be pressed down to the bottom of mold 218, the space between the sheet 209 and the platen 221 purposely being open to the atmosphere by avoiding too snug a fit between the hoop 215 and the platen 221 or, if found desirable, by cutting grooves across the top surface of hoop 215.

To prevent the sheet 209 from being drawn into the vacuum line a screen 226 is placed over vacuum line opening. Around the edge of the screen 226 is a boss 227 the purpose of which will be described hereinafter. After the sheet is thus shaped, it is chilled or cooled, for which purpose the mold 218 is supported in a shell 228 in such manner as to provide the water chamber 229, cool water entering the chamber through inlet 230 and discharging through outlet 231.

After the sheet 209 has been shaped against the inside surface of the mold 218, the platen 221 is raised out of the way of the operator and the operator, by means of hand roller 232, presses the sheet 209 against the boss 227 which results in scoring the sheet sufficiently to locate the center for application of the cover to the umbrella frame. The molded cover 209 is then removed together with the hoops 215 and 216. Next the hoops are broken apart and the cover 209 freed

therefrom. I have provided a form 233 on which to store the molded covers as shown in Fig. 4. The form is convex and of a curvature to correspond with the concave shape of the mold 218. One or more covers may be stored thereon and separators may be used if desired. The use of this storage form permits the removal of the molded cover from its mold while the cover is still warm thereby increasing the capacity for production of the mold as well as facilitating storage of the covers between the molding operation and the application to the umbrella frame.

In Figures 6, 7 and 8, I have shown another method of covering an umbrella on and between the umbrella ribs very similar to that just described except this latter method makes possible the turning inwardly of the edge of the cover 209 this being made possible by turning the edge of the cover away from the mold as shown in Fig. 7 rather than downwardly as is the case shown in Fig. 3. This latter method is practiced by placing the sheet 209 between outer hoop 241 and inner hoop 242 then placing the assembled hoops and cover in molding position on mold 243 and proceed as described in the case of the former method set out hereinabove. After the cover has been molded as shown in Fig. 8, its edges may be conveniently turned inwardly in assembly with an umbrella frame.

The edges of the cover may be re-enforced in any manner found desirable such as doubling the edges back on itself or adding reinforcement. Suitable tips of any practical type may be added to the outer ends of the radial ribs or other details of construction added after which the operator places the molded cover 209 in the working form 237 wherein it may be assembled with the umbrella frame.

Reference will now be made to Figs. 9 to 11, which illustrate the manner in which an orange or similar article may be completely enclosed in a unitary cover. As will be observed, two tubular cooperating members, 500 and 501 have secured in their open cooperating ends fine mesh screens, 502 and 503, in approximately the shape of the object to be covered. At the closed ends of said members 500 and 501 are ports 504 and 505, said ports communicating with pressure and vacuum tanks by means of three-way valves 506 and 507. Blanks of covering material, 510 and 511, of the type or nature previously mentioned, or any other suitable material, are applied over the faces of members 500 and 501 which are formed with depressions, 514 and 515 aligned with a vacuum tube, 516, which is suspended between the open faces of members 500 and 501, and extends only slightly beyond the edges of the said members. A heating element, 518, is adapted to be moved in between the blanks, 510 and 511, to heat said blanks and then to be removed, and the members, 500 and 501, are adapted to be moved toward each other until they contact. The vacuum line thru valves 507 and 509 is designed to create a vacuum within the members 500 and 501, and the pressure line thru said valves is designed to build up pressure in members 500 and 501. The operation of this form of the invention is as follows: The blanks 510 and 511 of covering material are placed in position over the open ends of members 500 and 501, where they are held by the rings 512 and 513 provided for that purpose. With the members 500 and 501 slightly spaced apart as in Fig. 9, the heating element is placed between the blanks to heat them after which the heating element is withdrawn and the vacuum valves

opened causing the blanks to be drawn back against the screens forming receiving cavities for the article to be covered. Next, the article to be covered is placed between the cavities and the members 500 and 501 are moved toward each other, which movement catches the article within the cavities and the movement is continued until the edges of the members 500 and 501, with the cover material between them, contact, which results in sealing or fusing the two blanks together except over the vacuum tube 516, and this tube extends into the space between the covered article and the cover. The vacuum line 516 is in operation as the cover blanks come together and thereby extract the air from between the cover and the covered object. Next, the small tube 516 is withdrawn and the small hole it leaves may be closed and sealed in any desired manner. Next, the pressure valve is opened and the members 500 and 501 are moved away from each other until the covered article is ejected, the pressure pressing the covering material firmly against the object being covered. To facilitate the removal of the article from the members 500 and 501, the clamping rings 512 and 513 may be disengaged from the turned edge portions of the blanks 510 and 511 which are now sealed together around the object. In the illustrated embodiment just described, the object is spherical, as an orange, but the invention is not limited in this respect since other objects and other shapes may be operated upon with equal success.

From the foregoing it will be evident that I have provided novel method steps and apparatus for covering various articles in whole or in part. In practicing the invention, the covering material is stretched, effecting economy and resulting in improved appearance, free from wrinkles. The invention is susceptible of numerous modifications other than those specifically described and illustrated, and the right is herein reserved to make such changes as fall within the scope of the appended claims without departing from the spirit of the invention.

This application is a true division from application Serial No. 193,214, filed February 28, 1938.

Having thus described my invention, what I claim is:

1. A method of covering an object in a film composed of material which when unheated is substantially inelastic but which when heated becomes highly elastic, including the steps of heating the film to render it sufficiently elastic, stretching the film while still elastic to conform it to the shape of the object to be covered independently of the object, and then while the film is still elastic applying it in stretched condition to the object and securing it thereon in such elastic stretched condition.

2. A method of covering an object in a film composed of material which when unheated is substantially inelastic but which when heated becomes highly elastic, including the steps of heating the film to render it sufficiently elastic, then after discontinuing the application of heat but while the film is still elastic stretching the film to conform it to the shape of the object independently of the object, and then while the film is still elastic applying it in stretched condition to the object and securing it thereon in such elastic stretched condition.

3. A method of covering an object, including the steps of providing a blank of heat-stretchable sheet material, anchoring the blank around the

perimeter of an individual unheated mold having a cavity approximating the shape of the object to be covered, heating the blank independently of the mold to render it sufficiently stretchable, stretching the heated blank into the unheated mold cavity independently of the object, and then attaching the blank in stretch-shaped condition to the object.

4. A method of covering an object, including the steps of providing a blank of heat-stretchable sheet material, anchoring the blank around the perimeter of an individual water-cooled mold cavity approximating the shape of the object to be covered, heating the blank independently of the molds to render it sufficiently stretchable, stretching the heated blank into the water-cooled mold cavity independently of the object, and then, after allowing the blank to cool and become set in its stretch-shaped condition, removing it from the mold cavity and attaching it to the object.

5. A method of wrapping an object in one continuous operation, including the steps of providing two blanks of heat-stretchable and heat-sealable sheet material, anchoring said blanks around the perimeters of the two unheated molds having complementary cavities approximating the shape of the object to be wrapped, heating the blanks concurrently independently of the molds to impart to them the requisite stretchable and sealable properties, then while the blanks still retain their heat stretchable property stretching them concurrently into the unheated mold cavities independently of the object, and thereafter while the blanks still retain their heat sealable property bringing the unheated mold cavities into mating relation to seal the stretch-shaped blanks together around the object as a unitary cover therefor.

6. A method of wrapping an object in one continuous operation, including the steps of providing two blanks of heat-stretchable and heat-sealable material, anchoring said blanks in an air-tight manner around the perimeters of two unheated molds having complementary cavities approximating the shape of the object to be wrapped, heating the blanks concurrently independently of the molds to impart to them the requisite stretchable and sealable properties, then while the blanks still retain their heat stretchable property creating a vacuum concurrently within the two mold cavities to stretch the blanks into the same and shape them accordingly, next placing the object to be wrapped within the mold cavities while maintaining the vacuum therein, and thereafter while the blanks still retain their heat sealable property bringing the mold cavities together into mating relation to seal the stretch-shaped blanks together around the object as a unitary cover therefor.

7. A method according to claim 6, including the additional steps of discontinuing the vacuum in the mold cavities after the stretch-shaped blanks have been sealed around the object as a unitary cover and introducing air under pressure into said cavities to press the cover into intimate contact with the enclosed object.

8. A method of wrapping an object in one continuous operation, including the steps of providing two substantially flat blanks of heat-stretch-

able and heat-sealable sheet material, heating said blanks concurrently to impart to them the requisite stretchable and sealable properties, then after discontinuing the application of heat to the blanks but while they still retain their heat stretchable property converting them concurrently by stretching into complementary cover sections approximating the shape of the object to be wrapped independently of the object, and thereafter while the blanks still retain their heat sealable property sealing them together around the object as a unitary cover.

9. A method according to claim 8 including the additional step of evacuating air trapped between the object and the cover before completing the sealing of the two cover sections.

10. A method of wrapping an object in a temporary protective film composed of material which when unheated is substantially inelastic but which when heated becomes highly elastic, including the steps of providing two blanks of such material to make up a complete wrapper which will entirely enclose the object, heating said blanks to render them elastic, stretching the two heated blanks simultaneously to increase their area and conform them to the shape of the object, and while the blanks are still elastic securing them in stretch-shaped condition simultaneously about the object to form the complete wrapper.

11. A method of wrapping an object in a temporary protective film composed of material which when unheated is substantially inelastic but which when heated becomes highly elastic, including the steps of providing two blanks of such material to make up a complete wrapper which will entirely enclose the object, heating said blanks to render them elastic, stretching the two heated blanks simultaneously to increase their area and conform them to the shape of the object, and while the blanks are still elastic securing them in stretch-shaped condition simultaneously about the object to form the complete wrapper by bringing portions of the blanks into heat-sealing contact.
